UNITED STATES PATENT OFFICE.

SAMUEL M. SCHWAB, JR., OF NEW YORK, N. Y.

DESIGN FOR A DECORATIVE FABRIC.

SPECIFICATION forming part of Design No. 21,735, dated July 26, 1892.

Application filed June 27, 1892. Serial No. 438,216. Term of patent 7 years.

To all whom it may concern:

Be it known that I, SAMUEL M. SCHWAB, Jr., a citizen of the United States, residing at New York city, in the county and State of New York, have invented and produced a new and original Design for a Decorative Fabric, of which the following is a specification, reference being had to the accompanying drawing, forming a part thereof, which represents a plan view of a piece of bunting or fabric decorated in accordance with my design.

The design consists of a series of contrasting panels, each panel containing two distinct figures—namely, a figure representing a shield

emblazoned with the stars and stripes and 15 the other figure a wreath of stars. The two figures are alternately arranged throughout the panels. As a minor feature of the design, the panels are made in groups of three, and the shields in the center panel are much 20 larger than in the side panels.

I claim—

The design for a decorative fabric, substantially as herein shown and described.

SAMUEL M. SCHWAB, JR.
